UNITED STATES PATENT OFFICE.

FRANK E. BROWN, OF WEBSTER CITY, IOWA.

ANKLE-BRACE FOR SKATES.

1,168,848.

Specification of Letters Patent. Patented Jan. 18, 1916.

Application filed July 9, 1913. Serial No. 778,143.

To all whom it may concern:

Be it known that I, FRANK E. BROWN, a citizen of the United States, residing at Webster City, in the county of Hamilton and State of Iowa, have invented certain new and useful Improvements in Ankle-Braces for Skates; and I do hereby declare the following to be a full, clear, and exact description of the invention, such as will enable others skilled in the art to which it appertains to make and use the same.

This invention is an ankle brace which is adapted to be placed on skates. Many persons, owing to weakness of the ankles, are deprived of the pleasures of skating and the purpose of the invention, therefore, is to relieve the ankle of the skater from lateral strain without depriving it of the necessary freedom of action.

A further aim of the invention resides in the application of the attachment to a skate to bring the supporting means at the side of the leg with its lower end pivoted above the horizontal plane of the skate foot-plate; to provide sufficient rigidity to the support, and to enable the supporting means to work in harmony with the ankle joint, and at the same time prevent chafing of the leg of the skater.

Further objects and advantages of the invention will appear from the following detailed description of the invention and novel features thereof particularly pointed out in the appended claims.

In the accompanying drawings, the preferred embodiments of the invention are illustrated, but it is to be understood that the constructions shown therein are for the purpose of illustration, only, and not as defining the limits of the invention.

Figure 1 is a side elevation showing the application of a brace to a skate. Fig. 2 is a view similar to Fig. 1 showing a modified form of supporting the ankle brace on a lady's skate. Fig. 3 is a side elevation of the brace and supporting means shown in Fig. 1. Fig. 4 is a front elevation of the heel plate of Fig. 1. Fig. 5 is a plan view of the heel plate of Fig. 1. Fig. 6 is a detail view of the heel plate which cooperates with the support of Fig. 2. Fig. 7 is a detail view in plan, of the heel engaging member separated from its normal abutting engagement with the heel of the skate, showing the clamping bar positioned in the channeled stem of the heel engaging member,

Fig. 8 is a side elevation, the parts being in the same position as in Fig. 7. Fig. 9 is a plan view of the heel engaging member removed from the skate.

The invention comprises a bar having means pivoted to the upper end thereof for securing the bar into substantial alinement with the leg of the skater. The lower end of the bar is pivoted at a point above the horizontal plane of the foot plate of the skate, thereby permitting an easy natural ankle movement on the part of the skater and at the same time affording a support for the ankle. The lower end of the bar is pivoted to a heel plate, one end of which is rigidly secured to the skate.

In the embodiment of the invention disclosed in Fig. 1, the ankle support is shown applied to a skate designed to be used on shoes worn by men or boys, and wherein the heel plate 10 of the skate is suitably mounted on the framework by angular lug plates 12. Each of these plates is provided with a horizontal part and a vertical part, the horizontal part serving as a support for the heel plate 10, while the vertical parts of the complementary lugs 12, clamp the blade or runner 26 of the skate between them. These angular lug plates 12 are provided with offset portions 27, which offset portions 27 form a channel 11 when the lug plates 12 are mounted upon the blade extension 28. Within this passage 11 may be positioned the channeled stem 13 of the heel engaging member of the ankle brace, said stem being provided with a channeled portion 29, as shown in Fig. 9, to permit the usual skate adjusting and clamping bar 15 to fit in the channel 29 and rotate therein for the purpose of operating the usual sole clamps of the skate.

The ankle brace comprises a depending portion 30 having a suitable aperture 31 formed therein in alinement with the channel 29 of the stem 13, which is preferably integral with the depending portion 30. Preferably formed integral with the depending portion 30, is an outwardly, forwardly and upwardly projecting arm 16 which is illustrated in Figs. 3, 4, 5, 7, 8 and 9, as having a bearing surface 17. This arm 16 is designed to be held in position by the stem 13 of the base, which is clamped between the lugs 12 and the bar 15, so that the arm 16 will extend around from the rear of the heel of the skate to one side thereof, the bearing surface 17 being positioned at a

point above the horizontal plane of the heel plate 10 of the skate, and terminating at a point in juxtaposition to the forward part of the heel of a skate, and at a point 5 below the ankle joint of the wearer. Pivotedly mounted on the clamping bar 15 is a locking plate 32 having a bearing surface 33, adapted to engage a face 34 of the depending portion 30 of the heel engaging 10 ankle brace. The heel engaging section 35 of the appliance is preferably positioned on a plane out of vertical alinement with the plate engaging face 34, as will be understood from Figs. 5, 7 and 8. This bearing 15 surface is so shaped that the plate 32 forms a double eccentric, which can be operated to lock the bar 15 at each quarter turn of said bar. This action of the part 33 of the plate 20 against the face 34 serves not only to tighten and lock the toe and heel clamp in place, but also tightens and holds the lower portion 25 of the ankle brace member firmly to the skate and shoe of the wearer, all by one operation of turning or pivoting the plate 32 to have the part 33 bear against the face 34.

It will be understood that the ankle supporting base will be substantially in abutting engagement with the ends of the lugs 12 30 during the adjustment of the bar 15 and its locking plate 32.

By reference to Figs. 7 and 8 of the drawings, the locking plate 32 is shown ready to adjust the ankle brace and the toe clamps, 35 while in Fig. 1, the parts have been adjusted and the locking plate 32 turned to one of its four locking positions. This locking plate may be turned downwardly, as in Fig. 1, upwardly or in a reverse position to that of 40 Fig. 1, or to the right or to the left, thereby permitting a quarter turn adjustment of the locking part.

A bar 18 is pivoted at its lower end to the bearing surface 17 of the arm 16, said pivot 45 being shown at 19 in the drawings. To the upper end of this bar 18 is pivoted suitable means for engaging the leg of the wearer. In the drawings, there is shown a broad bearing collar 20, having a wear plate 21 so secured thereto that it will be positioned at the side of the leg of the wearer, and a strap 22 for closing the collar around the leg. This wear plate 21 is pivoted at 23 to the upper end 50 of bar 18. In Figs. 2 and 6, the depending portion 30 and arm 16, which is designed more especially for skates which clamp directly to the heel, is omitted. In lieu of these parts 30, 16 there is provided a heel plate 24 comprising a single piece of metal bent at substantially right angles, the arm *a* thereof designed to be secured in any suitable manner to the under side of the heel foot plate, while the arm *b* thereof extends outwardly away from the heel foot plate. In 55 this construction, the bar 18 is pivoted at

25 to the arm *b* at a point above the horizontal plane of the heel plate 10, whereupon the same result is obtained in skates having the heel strap as with skates having the heel clamp. 70

Having thus described my invention, what I claim as new and desire to secure by Letters Patent, is:—

1. An ankle brace for skaters comprising a supporting bar having means pivoted near 75 the upper end thereof for attachment to the leg of the wearer, a base member adapted to be clamped at the rear end of the skate, said base member being provided with an upwardly and forwardly extended arm which 80 pivotally supports said bar at the side of the leg whereby the bar may be moved longitudinally of the skate, said pivotal connection between said arm and the supporting bar being at a point to one side of the foot 85 of the wearer and above the heel plate, and means to rigidly hold said base member against movement when the skate is clamped to the foot of the wearer.

2. An ankle brace for skaters comprising 90 a heel engaging member secured to the body of the skate and provided with an outwardly, forwardly and upwardly extended arm terminating above the horizontal plane of the heel plate of a skate and to one side 95 of the heel of the wearer, a supporting bar pivoted at its lower end to said arm and near the upper extremity of said heel plate, means for encircling the leg of the skater pivoted to the upper end of said bar, and 100 means to rigidly hold the heel engaging member against movement when the skate is clamped to the foot of the wearer.

3. An ankle brace for skaters comprising 105 a supporting bar, means pivoted near the upper extremity of said bar for holding the bar substantially parallel with and to one side of the leg of the skater, and a heel engaging member pivotally mounted near the lower extremity of the bar, said heel member 110 being clamped between a clamping bar and its support on a skate, said heel member comprising a base member and an outwardly, forwardly and upwardly extended arm. 115

4. An ankle brace for skaters comprising a supporting bar, means pivoted near the upper extremity of said bar for holding the bar substantially parallel with the leg of the skater and at the side thereof, and a heel 120 engaging member near the lower extremity of the bar and slidably mounted at the heel of a skate, means to lock said heel engaging member, said heel engaging member comprising a substantially straight base provided with an aperture for skate clamping means, a depending lug, and a forwardly and upwardly extended arm connected to said base to serve as a pivot to said supporting bar at the side of the heel of the skater. 125 130

5. An ankle brace for skaters comprising a supporting bar, means pivoted near the upper extremity of said bar for holding the bar substantially parallel with the leg of the
 5 skater, and a heel engaging member pivotally mounted near the lower extremity of the bar and slidably mounted at the heel of a skate, means to lock said heel engaging member, said heel member comprising a substantially straight base, a depending lug to be engaged by clamping means for a skate, a channeled plate retaining member extending from said lug and adapted to be clamped by means on the skate, and a curved forwardly and upwardly extended arm integral with the heel member and provided with a bearing surface near its free end for engaging said supporting bar at a point to support the bar at the side of the foot and
 10 leg of the wearer.
 6. A skate comprising toe and heel clamps, a threaded clamping bar, a locking plate pivoted at one end of said clamping bar and adapted to be operated at each
 15 quarter turn of said bar, a heel engaging member comprising a channeled stem to receive said clamping bar, a base provided with a plate engaging face, an arm connected to the base, and leg engaging means
 20 pivoted to said arm to permit of movement
 25

in a direction longitudinally of the skate and at the side of the leg of the skater while said base is retained in clamping engagement by the locking plate and said clamping bar.
 35

7. An attachment of the class described comprising a limb-encircling member, and an adjustable heel-clamping member, said heel-clamping member being provided with an elongated stem adapted to receive clamping means, an arm extending outwardly, forwardly and upwardly from said heel clamping member, and a connecting bar pivoted to said arm and to said limb-encircling member.
 40

8. A heel-clamping member for skates comprising heel engaging means, an elongated stem adapted to receive clamping means and an upwardly, outwardly and forwardly extending arm terminating at the side of the foot of the wearer and adapted to pivotally engage means for bracing the ankle.
 45

In testimony whereof, I affix my signature, in presence of two witnesses.
